DOUBLE ACTING HYDRAULIC JACK

Guy A. Countryman, Ashland, Ohio

Application August 12, 1933, Serial No. 684,873

5 Claims. (Cl. 60—52)

The invention relates to hydraulic jacks and more especially to a double acting jack which may be selectively raised or lowered by hydraulic power.

5 An object of the improvement is to provide a hydraulic jack adapted to be driven by hydraulic power to either raise or lower the jack as desired.

Another object is to provide a jack of this character having a hydraulic cylinder, with a piston 10 therein, and means for selectively admitting fluid to the cylinder upon either side of the piston.

A further object is to provide such a jack with a pair of valves controlling the raising and lowering of the jack, the valves being operated in 15 unison so that one valve opens as the other closes.

A still further object is to provide a jack having valves such as above referred to, in which the valves are reversely operated to open or closed position, and in which both valves may simultaneously assume a neutral position, whereby the 20 jack may be lowered by the weight of the body lifted thereby.

Another object of the invention is to provide a hydraulic jack having a safety valve which 25 permits the return of the fluid to the reservoir in the event too great a load is placed upon the jack.

A further object is to provide a hydraulic jack adapted for use in the straightening of automobile frames and the like, the jack being arranged 30 to pull portions of the automobile frame toward each other as well as to push opposite portions of the frame away from one another.

The above objects, together with others which 35 will later appear, may be attained by constructing the improved jack in the manner illustrated in the accompanying drawing, in which

Figure 1 is a vertical sectional view of the 40 double acting hydraulic jack embodying the invention, taken as on the line 1—1, Fig. 2;

Fig. 2, a plan sectional view of the improved jack indicated as on the line 2—2, Fig. 1;

Fig. 3, a fragmentary transverse sectional view taken as on the lines 3—3, Figs. 1 and 2;

Fig. 4, a fragmentary transverse sectional view taken as on the line 4—4, Fig. 2; and

Fig. 5, a fragmentary sectional view showing the connection of the fluid pipe from the pump to the upper end of the jack cylinder.

Similar numerals refer to similar parts throughout the drawing.

The improved jack to which the invention pertains may be formed of any suitable metal but in order to make the same sufficiently light in 55 weight that it is easily portable, the parts of

the jack are preferably formed of duralumin or other light weight alloy having sufficient strength for the purposes for which the jack is intended to be used.

The jack may be mounted upon a base in the form of a casting indicated generally at 10 of substantially oblong shape and having feet 11 and 12 at opposite ends for supporting the jack upon the ground or floor or other substantially horizontal surface when used as a lifting jack. 5

Located at the end of the base adjacent to the foot 11 is an upright annular flange 13 internally threaded to receive the lower threaded end of the hydraulic cylinder 15. The head 16 has the depending internally threaded flange 17 fixed 15 upon the threaded upper end of the cylinder 15 and a packing ring 18, of inverted substantially channel cross section is located within the upwardly disposed annular flange 19 formed upon the cylinder head 16, said packing ring surrounding the piston rod 20 and being held in place as by the screw ring 21. 20

The piston rod 20 has a shouldered portion 22 fixed upon its lower portion, the end of the rod being reduced and threaded as at 23 and 25 having the piston 24 held thereon by means of the nut 25, clamping the two fiber or leather washers 26 and the metal disk 27 therebetween. It will be noted that the washers 26 are provided with annular flanges 28, the flange of the 30 upper washer extending between the periphery of the shouldered portion 22 and the interior of the cylinder while the peripheral flange of the lower washer is located between the piston 24 and the interior of the cylinder, thus assuring a 35 tight fitting piston regardless of which side thereof the oil pressure is applied.

A boss 29 is formed upon the base at a point spaced from the annular flange 13 and is provided with an internally threaded socket 30 into 40 which is screwed the threaded lower end of the pump cylinder 31.

The pump is located within an oil reservoir including the shell 33 concentrically located with reference to the pump cylinder and having its 45 lower beveled end 34 received within the annular rib 35 formed upon the top of the base, the inner side of said rib being beveled as at 36 to receive the end portion 34 of the shell.

The top wall 37 of the reservoir has a central 50 opening 38 surrounding the pump cylinder and a depending peripheral flange 39 internally threaded for engagement with the threaded upper end of the shell 33, which together with the top wall is held clamped upon the base by means 55

of a nut 40 mounted upon the threaded upper portion 41 of the pump cylinder.

The pump plunger 42 is mounted within the cylinder 31 and has the fiber or leather washer 43 at its lower end provided with the peripheral flange 44, said washer being secured upon the lower end of the plunger as by the screw 45.

The plunger is slidably mounted through the stuffing box 46 provided at the upper end of the pump cylinder 31 and a nut 47 is fixed to the threaded upper end portion 48 of the plunger. Ears 49 may be formed upon the nut 47 between which is received the handle lever 50 pivoted to the ears 49 as by the pin 51, the inner end of said lever being pivoted as by the pin 52 to the upper end of a link 53 pivoted at its lower end as at 54 upon a lug 55 formed upon the top wall 37 or other stationary portion of the apparatus.

An inlet port 56 communicates with the lower end of the pump cylinder and leads to a horizontal passage 57 formed in the base casting, plugged at one end as by the screw 58, the other end thereof communicating with a vertical passage 59, the upturned end 60 of which communicates with the interior of the oil reservoir.

A valve seat 61 is formed in the passage 59 to receive the gravity operated ball check valve 62 which prevents oil from the pump from being forced back into the reservoir but permits oil from the reservoir to be sucked into the pump.

A safety valve is provided for overloading of the jack and may comprise a tube 63 closed at its upper end as by the screw plug 64, the lower end thereof communicating with the passage 59 above the ball 62. A valve seat 65 is formed in the tube 63, the check ball valve 66 being normally held downward thereon as by a coil spring 67, the tension on which may be adjusted by the screw 64.

Transverse openings 68 in the tube 63 form a communication between the interior of the tube, above the valve seat 65, and the interior of the oil reservoir 33. Thus, if a load greater than the capacity of the jack is placed upon the jack, the ball 66 will be raised by the oil pressure from the pump, permitting the oil to flow through the apertures 68 back into the reservoir, thus preventing straining of the jack.

A discharge passage 69 communicates with the lower end of the pump cylinder and leads downward through the base 19, communicating with the intermediate portion of a transverse passage 70 which terminates near one side of the base, the opposite end of the passage being closed as by the screw plug 71. A valve seat 72 is formed in the passage 69 above the junction with the transverse passage 70 and a ball check valve 73 is normally held seated against said valve seat by means of a coil spring 74, the tension upon which may be adjusted as by the screw 75.

The longitudinally disposed passages 76 and 77 communicate with the transverse passage 70, these passages being each closed at one end and having valve seats 78 and 79 respectively at their open ends to receive the ball valves 80 and 81 respectively, normally urged away from said valve seats as by the coil springs 82.

Transversely disposed chambers 83 and 84 communicate with the open ends of the passages 76 and 77 respectively and with the inlet ports 85 and 86 leading to the lower and upper ends respectively of the hydraulic cylinder 15, the upper port 86 communicating with the vertical pipe 87 which leads to a radial inlet port 88 terminating in the vertical passage 89 formed in the head 16 and

adapted to admit oil into the upper end of the cylinder 15 above the piston 22 and also to hold the packing ring 18 under pressure.

A pair of screw plugs 90 and 91 are mounted in internally threaded openings axially located with reference to the passages 76 and 77 respectively, each of said screw plugs having a central bore 92 communicating with a plurality of radial passages 93, the outer ends of which communicate with an annular groove 94 in the peripheral portion of the screw plug, ports 95 and 96 forming communication between the grooves of the screw plugs 90 and 91 respectively and the oil reservoir 33.

The bore 92 of each of the screw plugs communicates with the corresponding transverse passage 83 or 84, the screw plugs being provided at their ends with valve seats 97 and 98 respectively adapted to receive the ball valves 80 and 81 respectively.

A portion of the bore of each screw plug is threaded to receive the threaded portions 99 of the valve stems 100 and 101, which are adapted to contact with the balls 80 and 81 respectively for the purpose of moving said balls away from the seats 97 and 98 and toward the seats 78 and 79. The stems 100 and 101 are preferably arranged to be simultaneously operated in reverse directions and this may be accomplished by means of the gears 102 fixed upon the stems and meshing with each other. For the purpose of operating the stems, a handle 103 may be provided upon one stem whereby rotation thereof, through the gears 102, will operate both stems in opposite directions.

With the parts in the position shown in Fig. 2, the stem 100 holding the ball 80 against the seat 78 and the stem 101 being withdrawn out of contact with the ball 81 so that the spring 77 holds said ball against the seat 98, it will be seen that as the lever 50 is operated, the pump will force fluid through the passage 69, past the ball 73 and through the transverse passage 70. The passage 76 being closed by the ball 80, the oil is forced from the transverse passage 70 through the passage 77 past the ball 81 into the upper inlet port 86, thence through the upright pipe 87 to the upper end of the cylinder, forcing the plunger 20 downward.

By rotating the stems 100 and 101, by means of the handle 103, through the gearing 102, the stem 100 may be withdrawn from the ball 80 sufficiently to permit said ball to be moved away from the seat 78 but not against the seat 97 and the ball 81 will at the same time assume a corresponding position, thus placing the jack in a neutral position so that it cannot be pumped either up or down by means of the pump but permitting the weight upon the head 104 of the plunger 20 to slowly lower said plunger, the oil being forced from the lower end of the cylinder through the passage 85 and then through the bores 92 and radial openings 93 to the grooves 94 and through the passages 95 and 96 to the oil reservoir.

By turning the handle 103 further in this same direction the ball 80 may be seated against the seat 97 while the ball 81 is seated against the seat 79 whereby the operation of the pump plunger will force the fluid from the pump through the passage 69 and transverse passage 70 and longitudinal passage 76, past the ball 80 and through the lower inlet port 85 to the bottom of the jack cylinder 15 below the piston thereof, raising the plunger 20.

For the purpose of using the jack for straight-

ening automobile frames and the like, the base 10 may be provided with an internally threaded socket 105 beneath and axial with the cylinder 15 and the cap or lifting head 104 may be externally threaded as at 106 for the reception of threaded tubes or rods which may carry any suitable clamping means at their ends for engagement with opposite portions of an automobile frame or the like whereby the same may be drawn together or forced apart as desired.

It should be understood that instead of the particular ball valves 80 and 81 and threaded stems geared together for operating the same, any arrangement of valves reversely operated to close one valve and simultaneously open the other or to bring both valves to neutral position may be provided for accomplishing the invention without departing from the spirit thereof.

I claim:

20 1. A hydraulic jack including a cylinder, a plunger in the cylinder, a pump, an oil reservoir, passages forming communication between opposite ends of the cylinder and the pump, spaced valve seats in each passage, a communication between each of said passages and the oil reservoir, a valve in each passage, arranged to selectively seat against either valve seat, and means for simultaneously operating the valves to alternately seat said valves against oppositely disposed seat, and to neutral position spaced from both valve seats whereby the plunger may be lowered by the weight of a load thereon.

25 2. A hydraulic jack including a cylinder, a plunger in the cylinder, a pump, an oil reservoir, passages forming communication between opposite ends of the cylinder and the pump, spaced valve seats in each passage, a communication between each passage and the oil reservoir, a single ball valve in each passage arranged to selectively 30 seat against either valve seat, a spring normally urging each ball valve into a position against one seat to permit fluid from the pump to pass to the cylinder, a stem for contact with each ball to move the same against the pressure of the 35 spring to a position against the other valve seat, and means for simultaneously operating said stems in reverse directions to selectively divert fluid from the pump through one passage to the cylinder and through the other passage to the 40 oil reservoir.

45 3. A hydraulic jack including a cylinder, a plunger in the cylinder, a pump, an oil reservoir, passages forming communication between opposite ends of the cylinder and the pump, spaced

valve seats in each passage, a communication between each passage and the oil reservoir, a single ball valve in each passage arranged to selectively seat against either valve seat, a spring normally urging each ball valve into a position against one valve seat to permit fluid from the pump to pass to the cylinder, a stem for contact with each ball to move the same against the pressure of the spring to a position against the other valve seat, and means for simultaneously 5 operating said stems to alternately seat said valves against oppositely disposed seats, and to move both valves to neutral position away from both valve seats whereby the plunger may be lowered by the weight of a load thereon.

10 4. A hydraulic jack including a cylinder, a plunger in the cylinder, a pump, an oil reservoir, passages forming communication between opposite ends of the cylinder and the pump, spaced valve seats in each passage, a communication between each of said passages and the oil reservoir, a single ball valve in each passage arranged to selectively engage either valve seat, a spring for normally urging each ball to a position against one valve seat to permit fluid from the pump to pass to the cylinder, a screw threaded stem for contact with each ball to move the same against the pressure of the spring to a position against the other valve seat, and meshing gears upon said stems for simultaneously operating said stems in reverse direction to selectively operate the plunger in either direction by hydraulic pressure from the pump.

15 5. A hydraulic jack including a cylinder, a plunger in the cylinder, a pump, an oil reservoir, passages forming communication between opposite ends of the cylinder and the pump, spaced valve seats in each passage, a communication between each of said passages and the oil reservoir, a single ball valve in each passage arranged to selectively engage either valve seat, a spring for normally urging each ball to a position against one valve seat to permit fluid from the pump to pass to the cylinder, a screw threaded stem for contact with each ball to move the same against the pressure of the spring to a position against the other valve seat, and meshing gears upon said stems for simultaneously operating said stems to alternately seat said valves against oppositely disposed seats, and to move both valves 20 to neutral position spaced from both valve seats whereby the plunger may be lowered by the weight of a load thereon.
